UNITED STATES PATENT OFFICE.

HENRY F. COX, OF PHILADELPHIA, PENNSYLVANIA.

RAILWAY SWITCH AND SIGNAL INTERLOCKING APPARATUS.

SPECIFICATION forming part of Letters Patent No. 336,701, dated February 23, 1886.

Application filed March 25, 1885. Serial No. 160,045. (No model.)

To all whom it may concern:

Be it known that I, HENRY F. COX, of Philadelphia, Pennsylvania, have invented a new and useful Improvement in Railway Switch and Signal Interlocking Devices, of which the following is a full and true description, reference being had to the accompanying drawings, forming part of this specification.

In the switch and signal interlocking devices heretofore in use the interlocking of the switches, locks, and signals has in general been effected in a frame or frames at the signal tower or point of operation, and independent actuating levers and connections have, as a rule, been provided for each signal.

The object of my invention is to simplify and cheapen the construction expenses of such interlocking systems, and to render them at the same time easier and simpler in operation.

This I accomplish by means of interlocking frames, located in any convenient places in the connection, or at the foot of the signal-posts. Through or into each of these frames pass all of the switch facing-point lock or signal connections, which are elements of or relate to the route governed by the corresponding signal-post, each connection or element being attached to and directly actuating one or more of the locking-bars of the frame. These locking-bars are so arranged with respect to the flops which actuate the signals on the posts that the signal is locked to "danger" until all of the elements are in proper position, when the flop is released and the signal falls to "safety," while, on the other hand, the moving of any one of the elements out of the proper position will restore the signal to the "danger" position. As will be seen, by thus distributing the frames I am enabled to give the proper signals without the use of any independent signal levers or connections; or a single lever and line of connection may be used to actuate a series of signals on one or more posts. Two such levers and connecting-lines—one in each direction—will, as a rule, be sufficient to enable the operator to govern the signals to the same extent as in the older systems, where each signal is operated by an independent lever.

Where it is desired, in connection with my

system of interlocking switches with signals, to further interlock switches with each other, this last interlocking can best be accomplished at the lever-frame in the switch-house, as is now the custom.

Reference being now had to the drawings, in which Figure 1, Sheet 1, is a ground plan of an arrangement of switches, switch-actuating mechanism, and signal-posts, combined and arranged in accordance with my invention. Fig. 2, Sheet 2, is a front elevation of one of my signal-posts and interlocking-frames. Fig. 3 is a side elevation of the post and frame. Fig. 4 is a plan of the interlocking-frame. Fig. 5 is a perspective view of one of the flops. Fig. 6, Sheet 3, is an enlarged side view of one of my locking-frames. Fig. 7, Sheet 3, is an enlarged plan view of one of my locking-frames. Fig. 8, Sheet 3, is an enlarged view of one of the locking-dogs.

A is the signalman's or operator's cabin.

B B', &c., are signal-posts and interlocking frames.

C D E F G H I are lines of pipe or other devices for transmitting motion from the cabin to the different parts or elements of the system.

J J' J² are switch-connections.

K K' K² are switch-locks.

L is the base-plate of the interlocking frame.

M is the journal-bearing for the rockers or flops.

N is the rocker or flop, having a lever-arm, n, and a broad arm, n'. It is also provided with journals n².

O are the interlocking bars of the frames.

P are the interlocking dogs.

Q Q' are rods actuating the signals.

R R' are the signals.

S S' S², Sheet 3, are levers centrally pivoted at T T', and pivoted at their ends to sliding bars O.

In each of my interlocking frames I place as many rockers or flops N as there are signals on the post. These flops turn freely on their journals n², and are connected with the rods Q, which actuate the signals by means of their lever-arms n. The broad arms n' of the flops N extend downward and across the base-plate L. On suitable bearings at the bottom

of the base-plates L bars O extend longitudinally across it. Each of these bars is connected with and moved by the line of pipe or other actuating device, by means of which the 5 switch, facing-point lock, or other element of the system is actuated, and, as shown in the drawings, one such bar may be actuated solely by a signal-lever at the switchman's cabin. Secured to and extending upward from each 10 of the bars O are the locking-dogs P, each so arranged with respect to the broad arm n' of one of the flops N that when moved forward with the bar O, to which it is attached, it presses against the arm n' and causes the flop 15 N to turn on its journals, and by means of its lever-arm n and the attached rod Q move the signal to "danger" and keep it there until the bar and locking-dog are withdrawn.

Each of the elements of the route governed 20 by any one signal is connected with one of the bars O, and by means of locking-dogs P acts upon one of the flops N in such a manner that it is securely locked to "danger" by one or more of the dogs until all of the elements are in 25 proper position, when the flop is either at once released, permitting the signal to fall to "safety," or is locked simply by the dog actuated by the signal-lever in the cabin, and allowed to fall to "safety" when said lever is 30 moved.

Fig. 1 of the drawings illustrates my improved system as applied to a main track having three switches, each, as usual, provided with locks; and each of these switches 35 and locks is actuated through the usual connections by an independent lever in the switchman's house, A. From each of these switches and switch-locks connections are made with the interlocking frame B, which 40 governs the diverging signal-post, and each of them is an element of the main-track route, and must be in proper position before the signal governing that route can be allowed to show "safety." Each of the switch-actuating 45 connections I, G, and E is therefore connected with a bar, O, in the frame B, and each of the facing-point-lock connections from K, K', and K'' is also connected with a bar, O, in this frame, and on each of these six bars 50 O locking-dogs P are secured, in such positions with respect to the flop N, which governs the main-track signal, that the signal is locked in its "danger" position until each of the switches is closed and locked—that is to say, 55 the flop is locked to "danger" by six lock-dogs, P. The closing of each switch removes one of the locking-dogs, and the locking of each facing-point also removes one of the locking-dogs.

60 As shown in the drawings, Fig. 1, an additional bar, O, is introduced into the frame B, and actuated by a separate lever in the switch-house through the connection D. This is the bar represented by the lower bar, O, in Fig. 7, Sheet 3, and, as shown in the said drawings, as many locking-dogs P are attached to this bar as there are flops N in the frame. By

means of these locking-dogs each signal is held to "danger" after all the elements of its route are in proper position, and the position 70 of the signal is thus entirely within the control of the operator.

It is of course evident that the unlocking of any facing-point or opening of any switch will cause the main-track signal at B to be 75 moved and locked to "danger."

Three other flops, N, are shown in the frame B. These each relate to the route through one of the switches, and are governed by dogs P on the bars O, so placed as to require the route to be properly set and locked 80 before allowing the flop to fall.

Fig. 7 shows a proper arrangement of locking-dogs P to interlock and assure the safety of the routes governed by the four signals at 85 B. As shown in Figs. 1 and 7, the three switches are closed and the main track open; but the three facing-point locks are still open and the main-track signal is consequently locked to "danger" by the three dogs, P, governed by the facing-point locks, and by the dog on the bar O, governed by the special signal-lever D.

Signal B', Fig. 1, has but two connections—one from the pipe-line I, which controls the 95 switch J, and one from the signal-connection C. Signal B' has connections from I and G, as a train running out on the main track by B' would have reference to both of the switches J and J'. Signal B' has reference to all of the 100 switches, and consequently has connections from I, G, and E. No connections are shown from the facing-point locks to the signal-frames B', B'', B''', and B'', which all govern converging routes exclusively; and it is not 105 customary to use the facing-point locks in passing a train trailing on the switch.

The pipe-line C, Fig. 1, communicates with a bar, O, in each of the converging signal-frames B', B'', B''', and B'', and by means of this line 110 the signals governed by these frames are moved from "safety" to "danger," and their position controlled when the elements of the route are in proper position, in the same way that the signals governed by the frame B are controlled by the line D. At a diverging signal-post—such as B, Sheet 1—the movement of each switch must affect the locking of at least two of the signals, each relating to one of the two tracks connected by the switch; and it is 115 evident that without some more or less complicated intermediate interlocking between the switch and its facing-point lock, the bar O, connected with this facing-point lock, will lock and unlock both of these signals at the 120 same time, and also that where but a single signal-lever and connecting-line D is used to control the position of all of the diverging signals its movement will also simultaneously lock and unlock these two signals. At every 125 such diverging signal-point I therefore provide two bars O for each switch, uniting them together by means of centrally-pivoted levers—such as S, S', and S'', Figs. 6 and 7.

On one of these bars O, I place dogs P, arranged to lock those signals which should be locked when the switch is open, and on the other I place dogs P, arranged to lock those signals which should be locked when the switch is closed. The switch-actuating connection is secured to one of these bars O, and the second bar is of course given a reciprocating motion by means of the lever S; and, as will be at once seen from the drawings, the signals relating to the disconnected routes will necessarily be locked to "danger" by the same movement of the switch which opens the desired route and unlocks the signal which governs it.

In the drawings I have illustrated my invention in connection with a familiar system of transmitting motion from the actuating-levers by means of rocker-shafts, pipes on rollers, bell-cranks, &c.; but it is of course obvious that it may be used as well with any electric, pneumatic, hydraulic, or other method of transmitting power, and electric locking or releasing devices can also be employed as an additional guarantee that the route implied by a signal in its clear position is perfectly set and locked. My device also admits of the use of "special" or "permissive" locks, as they are called, which one skilled in the art will readily know how to apply.

It is of course obvious that any desired kind of signal may be used with my invention, the lanterns illustrated in the drawings having no greater relation to it than any other signal.

The interlocking frames with rockers N, bars O, locking-dogs P, and their attachments, which I have illustrated and described, will be, I believe, most simple and practicable for use in my interlocking system; but all of these devices may be modified in form and may be given and made to transmit motion in different ways and by means which, while not illustrated, will readily occur to a mechanic—as, for instance, the locking-dogs P, instead of being attached to bars O, as described, might be formed like a bell crank and caused to rotate on a pivot, one arm being attached to the actuating connection, while the other as it rose or fell would lock or unlock the flop; or rocker locking-bars may also be placed over the flops N in suitable bearings, and the locking-dogs attached to these bars would extend downward and engage with an upward-extending broad arm, n'. This arrangement will be found convenient when a large number of routes are interlocked in a single frame.

Having now described my invention, what I claim as new, and desire to secure by Letters Patent, is—

1. In a switch and signal interlocking system, substantially as described, the combination of separate interlocking frames for each signal-point with connections from each switch or facing-point lock, which forms an element of the route or routes governed by said signal-

point, in such a manner that the displacement of any and every element of a route governed by a signal results in locking such signal in its "danger" position.

2. In a switch and signal interlocking system, substantially as described, the combination of separate interlocking frames for each signal-point with connections from each switch or facing-point lock, which forms an element of the route or routes governed by said signal-point, in such a manner that the position of each signal is automatically controlled by the elements of its route.

3. In a switch and signal interlocking system, substantially as described, the combination of separate interlocking frames for each signal-point with connections from each switch or facing-point lock, which forms an element of the route or routes governed by said signal-point, in such a manner that the displacement of any element of its route will lock the governing signal to "danger," and an additional connection governing locking-dogs for two or more signals relating to routes in the same direction, and by means of which the position of such signals is controlled when the routes governed by them are clear.

4. The combination of locking-dogs connected with and governed by the elements of a route, with devices connected to and actuating the signal relating to the route in the way, substantially as shown and described, whereby the displacement of any element of the route indicated by a clear signal will restore the signal to its "danger" position without the intervention of a special signal connection.

5. In an interlocking system, substantially as described, the combination of a locking-bar attached to a switch-actuating connection and bearing locking-dogs governing the signals relating to routes opened by one position of the switch, with a second locking-bar bearing locking-dogs governing the signals relating to routes opened by the other position of the switch by means of a pivoted lever, whereby the second bar is given a simultaneous and opposite movement to that of the first, so that the unlocking of the signal or signals relating to the routes opened by one position of the switch will lock the signals relating to disconnected routes to "danger."

6. The combination of a signal or signals, with a rocker or rockers, N, and locking-dogs P, actuated by the elements of the route governed by the signals in such a way that each signal will remain locked to "danger" until all of its elements are in proper position, and will be at once moved from "safety" to "danger," and locked there by the displacement of any such element.

HENRY F. COX.
